UNITED STATES PATENT OFFICE.

CLAUS O. BRANDELL, OF CHICAGO, ILLINOIS, ASSIGNOR TO CONCRETE TILE MACHINERY COMPANY, OF CICERO, ILLINOIS, A CORPORATION OF ILLINOIS.

TILE-MAKING MACHINE.

Application filed August 29, 1924. Serial No. 734,902.

This invention relates to improvements in tile making machines, and has for its object to provide mechanism for use in the manufacture of concrete tile or the like, wherein the tile bearing pallets will be passed beneath an oiling device before charging, and thereafter conveyed to the charging mechanism to receive proper load of material.

Hitherto in such machines it has been customary to dip or otherwise coat pallets by hand, resulting in the use of considerable excess of oil, and requiring the service of an additional workman, in some instances at least, also requiring the use of a more expensive character of oil.

My present invention dispenses with this manual oiling, and coats each pallet in its passage toward the charging hopper with an adequate coating of oil, and at the same time provides means to collect and return for re-use of such oil as is not directed toward the pallet.

These and other objects will be more fully set forth and described in the following specification and shown in the accompanying drawings, in which—

Fig. 1 is a side elevation of a portion of a machine for manufacturing concrete roofing tile, showing my oiling mechanism applied thereto.

Fig. 2 is an end view of the same, only sufficient being shown to illustrate the relative location of the oiling mechanism.

Fig. 3 is a vertical section through the shield of the oiling device.

Fig. 4 is a side elevation of the oiling apparatus drawn to an enlarged scale, a portion of the shield being broken away for clearness.

Fig. 5 is an end view of the oiling device and associated mechanism, also drawn to an enlarged scale, a portion being broken away to illustrate the oil sump.

Like numerals refer to like elements throughout the drawings. 10 indicates generally a tile machine comprising the side frames 10^a and the transverse table portion 10^b. The table is centrally apertured at 10^c to accommodate the spaced conveyor chains 12, between which extend and to which are secured transverse supporting strips 13 carrying separating blades 14. These strips as shown are arranged in pairs, this arrangement with the spraying blades serving to

position and support individual pallets 55 which are positioned upon this conveyor mechanism at the front of the table, or the left hand end as viewed in Fig. 1, the upper run of the conveyor formed by the chains and strips moving in the direction of an arrow in Fig. 1. In Fig. 5 is illustrated in dotted lines the end contour of one form of pallet indicated by numeral 15. Mounted upon and extending upwardly from the table 10^b is the charging hopper 17, to which concrete is applied through the spout 18 or the like located thereabove. Secured to the front of the hopper 17 is the bracket, generally indicated by numeral 20, having the spaced journals 20^a and 20^b, in which is journaled a shaft 21 in suitable bearings, as indicated by dotted lines in Fig. 4, for example. Mounted between the bearings on the shaft 21 is the driving pulley 22 arranged for actuation by a belt (not shown) from a source of power. A shield 25 is provided having the rearwardly projecting flange 25^a, which is attached to the upper surface of bearing portion 20^a by thumb screws 26, or the like, permitting its ready attachment or detachment.

The shield 25 is provided with a slot 25^b at its rear side to permit passing of the same over the shaft 21. The sides of this slot diverge outwardly and downwardly, as clearly shown in Fig. 3. Mounted on the outer end of the shaft 21 in the shield 25 is the rotatable cup 28 having an aperture 28^a in one face. This cup is provided with staggered nozzles 29 in its outer periphery. While I do not wish to be restricted to any particular number of these nozzles, I have found four to be satisfactory in use. These nozzles are preferably threaded into the cup 28 to permit ready replacement or substitution of other nozzles with different sized apertures. The shield at its outer side 25^a is provided with the aperture 25^c in substantial alignment with the aperture 28^a of the cup 28, these apertures permitting the entrance of an inclined supply pipe 30, which in turn leads from the cylinder 31, having the sight window 31^a. Leading from the upper portion of cylinder 31 is pipe 32 with valve 32^a, this structure permitting a regulated flow of oil to the cylinder 31, visible through the window 31^a. The oil will flow from thence to the interior of the cup

28 through pipe 30. Rotation of the cup 28 at high speed exerts a centrifugal action upon the oil contained therein, so that at the proper speed the oil will be forced out 5 through the nozzles 29 and the sheet, somewhat in the nature of the sparks from a pinwheel. To accommodate the lag in this curtain or sheet of oil in the direction of rotation of the cup 28, the bottom 25^f of the shield 25 is inclined upwardly from one side, and is further provided with the opening 25^g above the conveyor, in which the sprayed or distributed oil passes to impinge upon pallets passing therebeneath. At the 15 divergent sides of the slot 25^b are provided the in-turned flanges 25^h and 25ⁱ, which serve as troughs to collect the oil impinging upon the inside wall of the shield, the same being conveyed to the sump 35, in which 20 the oil drains out through pipe 36, or is conveyed back to the source of supply for reuse. Similarly an inclined trough 25^k is provided at the front face of the shield as viewed in Fig. 4, for example, while around 25 the edge of aperture *e* the side wall is slightly in-turned as indicated by numeral 25^m, to prevent flow of the oil through the aperture. The sump 35 is provided with a central boss 35^a having a slot 35^b therethrough, in which 30 extends bolts 36 into engagement with the boss 25^e at the edge of shield 25, the slot permitting adjustment of the sump, the bolt serving to maintain the sump detachably secured to the shield.

35 As the pallets pass beneath the shield 25, they are coated with sufficient oil, but with my device I am able to control the degree of this coating with a fair amount of certainty, thereby economizing in the amount 40 of oil used and the centrifugal dispersion of the oil permits me to use oil of heavier body, with consequent less cost than that required for hand dipping. Furthermore, since the pallets are oiled just previously to 45 their passage through the charging hopper, there is no opportunity for the oil to become vaporized or drain off from the pallets as may happen when they are dipped in one location and conveyed by hand to the machine.

50 Should it be necessary to remove the shield 25 this may be readily done by removing the thumb screws 26, after which the slot 25^b will permit lifting of the shield from position, sufficient play being provided to permit tilting for clearance of the pipe 30.

55 It will be obvious that my invention is susceptible of modification, and I do not wish to be restricted to the form shown 60 except as defined in the appended claims.

What I claim is:

65 1. In combination, pallet conveying means, means to oil pallets conveyed thereby, said last named means comprising a spray member, a shield surrounding said member, said

shield being open above said conveying means.

2. In combination, pallet conveying means, means to oil pallets conveyed thereby, said last named means comprising a rotating spray member, a shield surrounding said member, said shield being provided with bottom face inclined upwardly from one side of said conveying means, said shield being provided with an opening in said face to permit escape of oil.

70 3. In combination, pallet conveying means, means to oil pallets conveyed thereby, said last named means comprising a rotating spray member, a shield surrounding said member, said shield being provided with a bottom face inclined upwardly from one side of said conveying means, said shield being provided with an opening in said face to permit escape of oil, said opening being of such size as to limit the escaping spray to substantially the transverse dimension of pallets passing therebeneath.

75 4. In combination, pallet conveying means, means to oil pallets conveyed thereby, said last named means comprising a spray member, a shield surrounding said member, said shield being open above said conveying means, said shield being removable from position surrounding said member.

80 5. In combination, pallet conveying means, means to oil pallets conveyed thereby, said last named means comprising a spray member, a shield surrounding said member, said shield being open above said conveying means, said shield being provided with means at its inner wall to collect oil impinging thereon.

85 6. In combination, pallet conveying means, means to oil pallets conveyed thereby, said last named means comprising a spray member, a shield surrounding said member, said shield being open above said conveying means, said shield being provided with means at its inner wall to collect oil impinging thereon, said last named means comprising troughs.

90 7. In combination, pallet conveying means, means to oil pallets conveyed thereby, said last named means comprising a spray member, a shield surrounding said member, said shield being open above said conveying means, said shield being provided with means at its inner wall to collect oil impinging thereon, said last named means comprising troughs, a sump associated with said shield, said troughs being arranged to convey collected oil thereto.

95 8. In combination, pallet conveying means, means to oil pallets conveyed thereby, said last named means comprising a spray member, a shield surrounding said member, said shield being open above said conveying means, said shield being provided with a second opening in a side face, said spray

member being provided with an opening in one face in alignment with said second shield opening, and an oil supply pipe extending through said openings.

5. A tile making machine including in combination pallet conveying means, a table, supporting means carried by said table, a bracket projecting therefrom, a shaft journalled in said bracket, a rotatable spray member attached to said shaft, and a shield surrounding said member.

10. A tile making machine including in combination pallet conveying means, a table, supporting means carried by said table, a bracket, a rotatable spray member attached

to said shaft, and a shield removably carried by said bracket.

11. In combination, pallet conveying means, means to oil pallets conveyed thereby comprising a spray member, a shield surrounding said member, said shield being provided with an opening in its bottom face over said conveying means, the sides of said shield converging upwardly from the bottom thereof, and means carried by said shield to collect the oil impinging upon the inner surfaces thereof.

In witness whereof, I hereunto subscribe my name to this specification.

CLAUSS O. BRANDELL.
